(54) BEE-HIVE

(76) Inventor: James M. Weeks

John M. Weeks Salesbury Vermont
Letters Patent.

The Schootable referred to in these Letters Patent and making part of the same, containing a description in the words of the said John M. Weeks, himself, of his improvement in the Bee Hive.

To all to whom these presents shall come,
Be it known that J. John M. Weeks of Salesbury, in the County of Addison and State of Vermont have invented a new and useful improvement in the construction of the Bee Hive, which shall hereafter be known by the name of the Vermont Bee Hive, and that the following is a full and exact description of said Hive: This Hive is a box made of inch boards forming two apartments, one in the lower part of the Hive in which the bees perform their ordinary labors, need a chamber for purposes hereinafter specified. It is composed of the following parts, to wit, one board 23 inches long - 13 inches wide, which forms the front of the hive. Two boards 23 inches long on the front edge - 15 inches wide on the top 13 $\frac{1}{4}$ inches wide at the base and 15 inches wide eight inches from the top, which form its two sides, one board 13 $\frac{1}{4}$ inches long 8 $\frac{1}{2}$ inches wide, which forms the back of the lower apartment to which a button is attached on its lower edge, to govern the bottom board and ventilate the hive. One board 16 $\frac{1}{2}$ inches square with a babbiting on the lower edge of its rear, 14 inches long corresponding with notches in the sides and partition board, to let in the door of the chamber, on which forms the top of the hive. One board 15 inches long 8 $\frac{1}{2}$ inches wide with a babbiting on the upper side of its rear edge, inserted, horizontally, into grooves in the sides of the hive, in eight inches from the top, which divides the hive into two equal

apartments, through this board are four apertures, affording the means of communication between the said apartments. One board 11 inches long and 5 $\frac{1}{2}$ inches wide, which forms the door, to the chamber of the hive, secured by a crossbar inserted into staples. One board fifteen inches square, which forms the bottom of the hive. This bottom board is suspended from the hive, by four hooks near the corners of the hive, the upper ends of which are attached to staples in the sides of the hive & the lower ends of which are inserted into staples, or brought around nails, attached to the sides of the bottom board. The positions of these last mentioned staples or nails are such, that when the hooks are attached to them, the lower parts of the hooks are, compared with their upper ends, inclined forward, so that when the bottom board is left unrestrained by the button in the rear of the hive, it will fall back, so far as to bring the hooks into a perpendicular position, whereby it will, by reason of the upward inclination of the back part of the bottom board, recede from the hive, and leave an opening all round. This opening will be greater or less, according to the greater or less inclination of the lower parts of the hooks above mentioned. Two slats are attached to the sides of the hive to support it on a frame, or in an apiary, as the case may be. The upper part of the hive is occupied by one or more domes as may be found convenient. Drainer A. 1, is made of boards one fourth of an inch thick the sides of which are 11 inches long and 5 $\frac{1}{2}$ inches wide. The ends 11 $\frac{1}{4}$ inches long and 5 $\frac{1}{2}$ inches wide, with windows in one or both, to enable the observer to ascertain the state of the bees. The top and bottom of which are 11 inches long and 12 $\frac{1}{4}$ inches wide with apertures through the bottom, corresponding in size and number to those through the floor of the chamber as before described.

Drainer A. 2, are made of like materials, the sides of which are 11 inches long & 5 $\frac{1}{2}$ inches wide. The ends 5 $\frac{1}{2}$ inches long and

and 5½ inches wide with a window at one or both ends at the top and bottom of which are 16 inches long and 6½ inches wide, with apertures through the bottom corresponding to those through the floor of the chamber. There are two metallic slides, each 16 inches long and 10½ inches wide, to be placed under the box, and there are four other metallic slides, each 11 inches long, and 5 inches wide, two of which are to be placed under each of the boxes. I. B. said slides to be used in the manner, and for the purpose hereinafter described. Thickness may be varied in its dimensions to suit the convenience or pleasure of the owner, and the number of drawers may be increased if so found necessary or expedient.

What I claim as my own invention and not previously known in the above described hive is:

First. The suspending of the bottom board from the hive by means of the staples and hooks and placing the same so under the bottom of the bottom board as is in the foregoing description that the hive may be opened and closed, for the purpose of ventilation, of preventing robbers by the bees from other hives and of cleaning the hive, at the pleasure of the owner. And while I do not claim as my own invention the said boxes, separately and independently of the combinations and uses hereinafter described, nor the use of single slides, I do claim, as my invention and improvement. Secondly, the double slides above mentioned, and the combination of the said boxes with the double slides, and the said combination of boxes and double slides in connection with the said suspended bottom board, and with the uses and purposes hereinafter specified, namely.

Specification of the uses of the drawers & slides & the manner of using them. - First: to remove extra pure honey, in which case the slides between the drawer you wish to remove, and the floor of the chamber so far as to intercept the

communication between the lower apartment and the drawer, then insert a second slide immediately above the former one, so far as to intercept the communication from the drawer downwards after which remove the drawer, — taking care to keep the apertures of the same closed by means of the upper slide; place the drawer thus removed a short distance from the apiary or hive and cover the window, remove the slide and the bees contained in the drawer ~~will~~ ^{will} in the drawer will soon return to the hive from whence the same was taken; insert an empty drawer in the place of the one removed, draw out the first slide and the bees will immediately resume their labors. In this way pure honey may be abstracted from the hive without loss of bees and without danger from them.

Secondly. To multiply swarms of bees. Take drawer, N. 1, containing bees and brood comb — place the same in a chamber of an empty hive — close the entrances of both hives so as to prevent the egis of the bees — let them remain three or four days supplying each hive daily with a clean water then open the entrances of each and you have the swarms or separate colonies. — Thirdly. To equalize swarms by doubling, halving or quadrupling them; when swarms come forth and are found to be very unequal in numbers and it is desirable that each colony should be made equal on the same apiary, put a small swarm into the lower apartment of an empty hive — a second small swarm into drawer N. 2, a third small swarm if necessary, into another drawer N. 3. Then place the drawers in the chamber of the hive — with draw the slides and the two or three swarms as the case may be, will immediately amalgamate in the lower apartment of the hive, in which case one or more smaller swarms may be added, as may be found necessary.

Fourthly. To make queen bees and keep them out, hand

honey for the use of the owners; Take drawers N.º. 2 containing bees and brood comb—place the same in the chamber of an empty hive—keep the entrance of the hive closed for three or four days, giving the bees clean water every day—then open the hive and they have a queen laying state and will immediately resume their ordinary labor, and increase and support their young quite during the season.

Fifthly—To supply swarms which have lost their queen, with a new one; insert the drawer containing a queen prepared as in the foregoing experiment in the chamber of the hive to be supplied and the object is accomplished.

Sixthly—To prevent the depredations of the Bee moth when a swarm leaves a hive and the same is thereby so reduced in number that a quantity of the comb is left unoccupied, take the queen from the swarm which has issued from the hive—collect the rest of the swarm in a drawer and replace them in the chamber of the hive from which the swarm issued and the design is effected, in as much as the moth does not commit its depredations to any considerable extent except where there are unoccupied combs.

Note. The slides and drawers are to be used in all experiments in the manner described in the first of the foregoing uses, and slide N.º. 1, is to be used only with drawer N.º. 1.
